UNITED STATES PATENT OFFICE.

AUGUSTINE F. FITZ GERALD, OF BROOKLYN, ASSIGNOR TO THE VAN DERVEER & HOLMES BISCUIT COMPANY, OF NEW YORK, N. Y.

GLASS-CLEANING MACHINE.

SPECIFICATION forming part of Letters Patent No. 392,600, dated November 13, 1888.

Application filed December 28, 1887. Serial No. 259,273. (No model.)

To all whom it may concern:

Be it known that I, AUGUSTINE F. FITZ GERALD, a citizen of the United States, residing in the city of Brooklyn, county of Kings, 5 and State of New York, have invented a new and useful Improvement in Glass-Cleaning Machines, of which the following is a full, clear, and exact specification, reference being had to the accompanying drawings, which 10 form a part hereof.

My invention relates to a machine for cleaning plates of glass or similar material; and its object is to enable such plates to be cleaned from oil, dirt, and other foreign substances, 15 and prepared for use in a convenient, quick, and economical manner.

Figure 1 is a side elevation of the machine with one end of the box or frame broken away. Fig. 2 is a vertical section showing the rollers 20 and buffers between which the plates of glass are passed. Fig. 3 is an elevation view of the end of the machine at which the glass is fed to the machine. Fig. 4 is a sectional view of one of the buffers, showing its construction 25 and taken through and parallel with its axis. Fig. 5 is an enlarged sectional view of one of the rings or disks of buffing material of which the buffers are made; and Fig. 6 is a transverse vertical section of the machine, taken 30 through the axes of the rear rollers.

Similar letters refer to similar parts throughout the several views.

The frame of my improved machine consists of the sides L L', the table I, and its supporting-bracket K, the sliding end piece, M, which is adapted to be removed to clean the machine or for any other purpose, and which has the slot m, through which the plates are fed to the rollers, and the fixed end piece, O. 40 These parts may be made of any suitable material, such as wood or iron.

A B are cleaning-buffers, which are adapted to revolve in contact with the surfaces of the plates to be cleaned. These buffers consist of 45 a central shaft, r, surrounded by the rings of buffing material t, the whole suitably mounted in the sides L L' of the machine.

s s are collars adapted to press against the rings of buffing material and hold them in 50 place.

v v are lock-nuts for the collars s s.

p p are small rods which pass through holes p' p', Fig. 5, in the rings of buffing material and into similar holes in the collars s s, and are held therein by nuts or other suitable 55 devices. I prefer to make the cleaning portions of the buffers of rings of suitable material—such as cotton cloth—having a central hole or aperture adapted in size to the diameter of the shaft upon which they are to be 60 mounted.

C, D, E, and F are rollers suitably mounted on shafts with journals in the sides L L' of the machine, the shafts being preferably parallel to the shafts r r' of the buffers A and B. 65 These rollers are made of or covered with rubber or other elastic material. The bearings of the rollers D and F are fixed in the sides of L L' of the frame. The rollers C and E have their bearings in boxes sliding in 70 the sides L L', and are adjusted by hand-screws H H', having shouldered heads n fitting in these boxes and resting on springs w, as shown in Figs. 1 and 6. The screws H H' have hand-wheels at their upper ends, and by 75 means of their spring-connections with the rollers not only may be used to adjust the rollers for different thicknesses of plates, but also, in conjunction with the elastic surfaces of the rollers, insure the maintenance of an elastic and yielding pressure upon the plates, 80 avoiding all liability of breaking the plates, while at the same time tightly gripping them.

The buffing-rollers A and B have their bearings in boxes sliding in the sides L L'. These 85 boxes are similar in construction to the boxes of the rollers C and E, and are adjusted in like manner by hand-screws G G', corresponding to the hand-screws H H'. The shouldered heads n of these hand-screws are fitted to rotate only in the bearing-boxes. The bearings of the upper buffing-roller are shown in Fig. 4, those of the lower buffing-roller being of 90 identically the same construction.

As the lower rollers, D and F, have fixed 95 bearings, it is obvious that the lower buffing-roller, B, requires but little adjustment. Indeed, this adjustment need only be sufficient to suitably vary its pressure upon a plane practically fixed in position.

a is a pulley rigidly attached to one end of the shaft r, which carries the buffer A, and is 100

adapted to be driven by a belt, l . b is a similar pulley rigidly attached to one end of the shaft r of the buffer B, and is adapted to be driven by a belt, l' .

5 b' is a worm which is attached to one end of the shaft r of the buffer B.

k and k' are shafts supported in the journals i , i , i , and i , which are rigidly secured to the side L of the machine. To one end of each of 10 these shafts is attached a worm-wheel, g g' , adapted to engage with and be driven by the worm b' . To the other ends of these shafts k and k' are attached the bevel gear-wheels h and h' . As the axes of these worm-wheels g 15 and g' are inclined at an acute angle to the line of adjustment of the lower buffering-roller, B, and the teeth are deeply cut in the worm and wheels, the slight adjustment which may be given to the lower buffering-roller does not 20 interfere with the proper working of the gear.

On one end of each of the shafts which carry the rollers D and F are rigidly attached the bevel gear-wheels d and f , respectively, which are adapted to gear with and be driven by the 25 bevel gear-wheels h and h' . The bevel gear-wheel f is also made with ordinary or straight gear-teeth.

e is an ordinary gear-wheel fastened rigidly to the shaft which carries the roller E. It is 30 adapted to gear with and be driven by the ordinary gear-teeth made on the bevel gear-wheel f .

The table I is so arranged that when the plates are held by the rollers C and D the table 35 I will be slightly below the plate, so that there is no danger of the plate being broken by pressure against the table I. This space between the plate and the table I should be less than the thickness of the plates which are being 40 fed into the machine, so that the plate that is next fed to the rollers will not slide under the plate already in the machine, thus avoiding the danger of the breakage of the plates, which might result if the end of one 45 plate were pressed down upon the end of the following plate.

The operation of the machine is as follows: The buffers A and B are by the belts l and l' set revolving, preferably in opposite directions, and the worm b' thus causes the rollers 50 D, E, and F to revolve in the direction shown by the arrows, Fig. 2, through and by means of the intervening worm-wheel, g g' , the shafts k k' , the bevel gear-wheels h' , d , h , and f , and 55 the ordinary toothed gear-wheel, e . The plate to be cleaned is laid, with one of its edges preferably parallel to the rollers C and D, on the table I. The plate is then pushed by the operator until the roller D acts upon it and draws 60 it between the rollers D and C, thus slightly raising it from the table I. The plate is then forced by the rollers C and D between the buffers A and B, which do the cleaning, and before the rollers C and D loose their grip on the 65 plate the rollers E and F grip the plate, all as

shown at q q' , Fig. 2, and then the rollers E and F act to remove the plate from the buffers A and B. When the plate is in the machine in the position shown at q q' , Fig. 2, the next plate is laid on the table I and pushed by the 70 operator between the rollers D and C, so that it immediately follows the plate already in the machine.

It is obvious that the work will be accomplished whether the surface of the buffers A 75 and B moves in the same direction with the glass or in a contrary direction; also, whether the two rollers C and D are geared together or whether one is given a positive motion and the other serves only to keep the plates in contact 80 with the one which is geared and has a positive motion; also, whether the two rollers E and F are geared together or whether one is given a positive motion and the other serves only to keep the plates in contact with the one 85 which is geared and has a positive motion.

The worm and worm-wheels and the bevel-gearing may, if desired, be replaced by other suitable devices—such as chains or belts—without affecting the principle of my invention. 90

In place of constructing the buffers in the manner shown, with rings of buffering material, any other suitable construction of the buffers may be adopted—as, for example, the cleaning-surface of the buffers may be formed by wrapping or otherwise fastening cloth or leather or other suitable material of sufficient thickness upon the surface of the buffer; but I prefer to construct my buffers in the manner already 100 described.

What I claim as new, and desire to secure by Letters Patent, is—

1. In a machine for cleaning plates of glass or similar articles, in combination, the revolving buffers A and B, adjustably mounted in the frame of the machine, the feed-rollers C and D, having elastic surfaces, the roller C being adjustably mounted in the frame, and the rollers E and F, also having elastic surfaces, the roller E being adjustably mounted in the frame, the rollers C and E being held in bearings having a spring connected with the frame, substantially as shown and described. 105

2. In a machine for cleaning plates of glass or similar articles, in combination, the revolving buffers A and B, adjustably mounted in the frame of the machine, the feed-rollers C and D, having elastic bearing-surfaces, the roller C being adjustably mounted in the frame, 115 the rollers E and F, also having elastic surfaces, the roller E being adjustably mounted in the frame, and the table I, having its upper surface slightly below the highest surface of the roller D, substantially as shown and described. 120
